COUPLED CIRCUITS

Alfred W. Barber, Flushing, N. Y.

Application February 3, 1936, Serial No. 62,074

15 Claims. (Cl. 179—171)

This present invention of mine concerns improvements in carrier wave receiver circuits. It particularly concerns methods of, and means for, the automatic control of radio or carrier wave receiver response by means of automatic interstage circuit coupling control.

One object of my invention is to provide means for the automatic control of radio or carrier wave receiver or amplifier response. Another object is to provide automatic control of interstage circuit coupling in carrier wave amplifiers. A further object is to provide automatic circuit coupling means easily controlled over a wide range of responses.

15 In my copending application for Letters Patent dated January 27, 1936 and entitled "Coupled circuit systems" Serial No. 61,458, I have shown circuit coupling means consisting of the grid to cathode capacity of a thermionic vacuum tube. I have also shown how the grid to cathode capacity and hence the coupling may be controlled by varying the grid bias in the coupling tube. Further, I have shown how this control may be effected from the rectified signal, and hence the coupling and amplifier response made to automatically vary with the strength of the received signal. My present invention is a system devised for the same purpose but showing a more sensitive control characteristic.

30 In radio and carrier wave amplifiers the interstage selective means usually consists of pairs of tuned circuits. If the two circuits comprising each pair are coupled together by varying amounts, three general types of response are possible. With less than a particular coupling called "critical", the response of two circuits tuned to the same frequency is a single peak but the amplitude of transmission becomes less as the coupling is decreased. At critical coupling the response is still a single peak but with some broadening of the peak and a maximum amplitude of transmission. If the coupling is increased above critical, the amplitude of response remains the same but a second peak appears and as the coupling is increased, the frequency of the second response moves further away from the tuning frequency. Due to receiving conditions, it is often necessary to use the maximum obtainable selectivity in a radio receiver which 40 requires critical coupling or less between interstage circuits. However, under this condition most systems produce serious attenuation of modulation frequencies above 3000 cycles. In some receivers manual means have been provided for increasing coupling and hence broad-

ening response when receiving conditions permit. Since the possibility of using broadened response usually occurs on strong stations, I have found it possible to control coupling automatically as a function of signal strength and thus do away with manual control.

In my copending application, I have shown how automatic coupling may be provided in the control of thermionic vacuum tube input capacity. The dynamic input capacity of a thermionic 10 vacuum tube depends mainly on the grid to plate capacity and grid to plate gain of the tube. Since the tube gain may be controlled by means of its grid bias, the input capacity may also be controlled by grid bias changes. If the bias is 15 derived, in part, from the rectified signal traversing the receiver or amplifier, the coupling and hence band-pass characteristics may be made to automatically follow the received signal strength. My present invention makes use of this same 20 controlled tube input capacity but the sensitivity of the control is greatly increased by using resonant or partly resonant coupling means. The tube input capacity is used in conjunction with inductive coupling means and by means of 25 series resonance, the coupling is made to vary more rapidly as a function of tube gain than in the simple common impedance type of coupling. I have found it possible to vary a 500 k. c. tuned 30 pair of circuits from a single peaked response to a 30 k. c. band-pass by varying the grid bias of a 1500 micromho mutual conductance vacuum tube by an amount to cause the plate current to change from zero to 5 milliamperes.

The appended claims set forth, in particular, 35 the novel features to be found in this invention. The following description, however, when taken in connection with the drawing, will serve to set forth the theory and mode of operation of my invention.

40 In the drawing,

Fig. 1 shows the circuit of a radio receiver, up to and including the second detector, embodying my invention.

Fig. 2 shows the equivalent circuit of two tuned 45 circuits coupled by my present system.

Fig. 3 shows a circuit equivalent to Fig. 2.

Fig. 4 shows curves characteristic of the operation of my invention.

In Fig. 1, I have shown a superheterodyne receiver exclusive of the audio amplifier and loud speaker. The tube complement consists of a first detector 1, intermediate frequency amplifiers 2 and 3, second detector 4, oscillator 5 and coupling tubes 6 and 7. The first detector-oscillator 50

circuits are conventional. $+E_B$ denotes points of connection of plate voltage supply and $+E_D$ denotes points of connection of screen voltage supply. Between plate 8 of the first detector 1 and the plate voltage supply is connected a tuned circuit consisting of coil 9 tuned by condenser 10. Coil 9 and condenser 10 form the tuned primary of an interstage transformer. Coil 11 tuned by condenser 12 forms the tuned secondary of the 10 interstage transformer feeding grid 13 of the following amplifier tube 2. Coupling between coils 9 and 11 is accomplished by means of coil 14 magnetically coupled to primary coil and coil 15 magnetically coupled to secondary coil 11 and an 15 external series impedance thru condenser 16. The voltage induced in coil 14 from coil 9 causes a current to flow in coil 15 of a magnitude depending on the impedances of coils 14 and 15 and the impedance between the lower end of coil 14 and ground. This impedance is condenser 16 in series with the input or grid to cathode dynamic impedance of tube 6. This input impedance is essentially a capacity reactance. Condenser 16 is shown as a blocking condenser having 20 a capacity large compared to the tube input capacity. The controlled current flowing in the series circuit flows thru coil 15 inducing a voltage in coil 11 which is a function of the current. 25 The equivalent circuit of this coupling system is shown in Fig. 2 where the primary circuit consists of inductance L_1 tuned by condenser C_1 , and the secondary circuit consists of inductance L_4 tuned by condenser C_4 . Coupling between L_1 and L_4 is accomplished by the coupling link consisting of inductances L_2 and L_3 and condenser C_{23} all in series. L_2 is magnetically coupled to L_1 and L_3 is magnetically coupled to L_4 . L_1 induces a voltage in L_2 and a current flows in the L_2 , L_3 , C_{23} series circuit. Since C_{23} is variable the current 30 depends on the value of C_{23} and the voltage induced in L_4 depends on this current flowing in L_3 . It should be noted that if at the operating frequency, C_{23} resonates L_2 and L_3 in series, a series resonant circuit is produced in which the 35 series current increases very rapidly as C_{23} is varied. C_{23} represents the grid to cathode capacity of tube 6 or 7 in Fig. 1.

Fig. 4 shows a plot of reactance against bias where bias designates the variable component of 40 the bias applied to the grids of the coupling tubes 6 or 7. The horizontal axis may also be condenser capacity in order to explain Fig. 2. L_ω is the reactance of L_2 and L_3 (or coil 14 and coil 15) in series.

$$L_\omega = \frac{1}{C_\omega}$$

is the reactance of C_{23} (or the input capacity of tubes 6 or 7) as the capacity is varied. The reactance of the series circuit is then shown by the 50 curve

$$L_\omega = \frac{1}{C_\omega}$$

The increase in sensitivity of the tuning effect 55 over the simple self-reactance coupling is shown by comparing the last two curves. Starting with a bias or condenser setting a the bias or capacity alone must be varied to point c in order to halve the series coupling reactance. However, with the inductance added the reactance is halved in going from a to b on the

$$L_\omega = \frac{1}{C_\omega}$$

curve. The apparent sharpening of control 60 becomes greater as the series resonant point is ap-

proached and by proper choice of circuit elements a wide range of control slopes may be obtained.

Fig. 3 shows a circuit equivalent to Fig. 2 in terms of mutual and leakage inductance all reduced to unity turns ratio. M_{12} is the mutual inductance between L_1 and L_2 and M_{34} is the mutual inductance between L_3 and L_4 . This circuit shows that the series resonant coupling impedance is not accurately L_2 , L_3 and C_{23} but is $L_2 \pm M_{12}$ plus $L_3 \pm M_{34}$ and C_{23} in series. Looking at 10 the system thus from the standpoint of an equivalent circuit, C_{23} is equivalent to a "high side" coupling reactance and resonates with the leakage reactance of L_2 and L_3 to provide a sharp coupling effect.

Returning to Fig. 1 the input capacity of tube 6 is equivalent to condenser C_{23} of Figs. 2, 3 and 4. This input capacity depends on the tube characteristics, operating voltages, plate load and grid to plate capacity. Actually it depends 20 on the tube grid to plate gain and grid to plate capacity. With no external applied bias the tube gain depends on the tube characteristics, plate voltage E_B , cathode bias E_c and plate load resistor 17. While I have found the simple resistor 17 to be a satisfactory load, a complex impedance may be used. The tube is not limited to a triode although I prefer one. Tube 6 is shown having a cathode 18, heated by means not shown, a control grid 19 and a plate 20. The grid to 30 plate capacity 21 may be taken to represent the internal tube capacity plus external added capacity. The initial bias is provided by battery E_c in the cathode circuit. The control bias is supplied thru the resistor 22. Condensers 23 and 35 24 are by-pass condensers. The circuit is designed so that with no external applied bias thru resistors 22 and 25, the circuit coupling is the minimum desired which will in general be critical coupling, for maximum selectivity and gain. 40 If an external positive bias is applied to grid 19, the gain of tube 6 is increased increasing its input capacity. Increasing the input capacity increases the current flowing in the coupling circuit increasing the coupling. As the coupling is 45 increased over critical, a double peak appears in the response producing a band-pass characteristic.

The same coupling system is shown between tubes 2 and 3 that was shown and described between tubes 1 and 2. Tube 3 feeds a tuned output circuit consisting of inductance 26 tuned by condenser 27. The double diode second detector 4 is fed from coils 28 and 29 magnetically coupled to coil 26. The voltage across coil 28 is impressed 55 on the diode formed by plate 30 and cathode 31 thru the load by-pass condenser 32. The load resistor 33 develops a rectified current voltage drop which may be used for automatic volume control of tubes 2 and 3 by applying the drop to 60 grids 13 thru the filter consisting of resistors 34 and 35 and the condensers 36 and 37. The audio voltage for actuating the audio amplifier and speaker may also be obtained from the drop across resistor 33 or a separate rectifier may be employed. 65

The voltage across coil 29 is applied to the diode consisting of plate 38 and cathode 39 thru the by-pass condenser 40. The rectified output is a drop thru resistor 41 and the direct current component is filtered out by means of resistors 70 25 and condensers 23. This direct current component is proportional to the signal output from tube 3 and is a function of the signal picked up by antenna A. Since the cathode 39 end of load resistor 41 becomes more positive the greater the 75

signal received, the external bias supplied by rectification to tubes 6 and 7 is more positive the greater the signal. As shown above the more positive the external bias, the greater the input capacity to tubes 6 and 7 and the greater the coupling between the interstage circuits. Thus the system provides a response which is a function of the received signal and the stronger the received signal the wider the response band and the better the amplifier fidelity.

While not in any way intended to limit the scope of my invention, I have found the following constants to give the indicated expansion:

Tube 6 or 7 mutual conductance at normal bias 1450

Resistor 22	ohms	500,000
Bias E_c	volts	25
Plate voltage E_b	do	250
Resistor 17	ohms	400
External part of condenser 21	mmf	50
Internal part of condenser 21	mmf	6
Condenser 16	mmf	2000
Coil 9	mh	1
Coil 11	mh	1
Coil 14	mh	0.3
Coil 15	mh	0.3
Condenser 10 to tune coil 9 to 547 k. c.		
Condenser 12 to tune coil 11 to 547 k. c.		

Coupling between coils 9 and 14 and between coils 11 and 15 close.

Coupling with no external grid bias very nearly critical giving single response peak, with plate current zero.

With external bias to give plate current 5 ma. over coupling produced giving two peaks separated 30 k. c.

A set of typical results is here shown as peak frequencies for various coupling tube plate currents.

0 ma.	5 ma.	20 ma.
Peak 547 k. c.	Peak 547 k. c.	Peak 547 k. c.
Peak 517 k. c.	Peak 497 k. c.	

An effective delayed expansion may be produced by increasing E_c beyond cut-off. Since no expansion will take place until the coupling tubes 6 and 7 draw plate current, the delay depends on the amount the bias E_c exceeds the cut-off bias of tubes 6 and 7. Suppose for instance 25 volts is the bias required for cut-off then if E_c is made 40 volts it will take 15 volts of external bias to bring 55 the 40 volts to a net 25 volt bias. If 15 volts on the rectifier corresponds to 1 millivolt on the antenna, no expansion will take place until the received signal exceeds 1 millivolt. As the net bias is reduced below 25 volts the coupling increases expanding the receiver response.

While I have shown my automatic coupling system applied to intermediate frequency amplifier circuits, it is by no means thus limited but may be applied to variably tuned stages such as 65 in a tuned radio frequency receiver or in the pre-selector circuits of a superheterodyne. Many combinations are possible such as equal expansion control on two intermediate frequency stages; a control with a different delay control 70 on a third intermediate stage and a control with a still different delay value on the pre-selector circuits.

While I have described only one system whereby my invention may be carried into effect and have 75 pointed out a few possible variations, it will be

apparent to one skilled in the art that many modifications are possible without departing from its spirit and scope as set forth in the appended claims.

What I claim is:

1. In a selective carrier wave amplifier, means for varying the selectivity of said amplifier comprising the combination of at least two thermionic vacuum tube repeaters, a resonant circuit receiving the output of one of said repeaters, a second 10 resonant circuit connected across the input of another of said repeaters, a series circuit comprising two coils, a condenser and the grid to cathode impedance of a third thermionic vacuum tube comprising at least a grid, cathode and 15 plate wherein one of said coils is magnetically coupled to one of said resonant circuits and the other of said coils is magnetically coupled to the other of said resonant circuits whereby energy is transferred from one of said resonant circuits to 20 the other wherein said impedance includes a capacity reactance component of greater magnitude than the combined inductive reactances of said two coils at the resonant frequency of at least one of said resonant circuits. 25

2. The combination as set forth in claim 1 and including means for supplying a bias to the grid of said third vacuum tube at least in part derived by rectifying the signal traversing said amplifier.

3. The combination as set forth in claim 1 and including means for applying a bias to the grid of said third vacuum tube greater than that required for plate current cut-off for all received signals below a predetermined level. 30

4. In a radio receiver employing thermionic vacuum tube repeaters, an interstage coupling circuit comprising tuned input and output coils and a link circuit, a thermionic vacuum tube comprising at least a grid, cathode and plate, said link circuit including in series connection two coils and the grid to cathode impedance of the last said thermionic vacuum tube all connected in series, wherein said link is adapted to transfer energy between said tuned circuits by virtue of magnetic coupling between one of said coils and said output circuit, the coupling between other of said coils and said input circuit and the series connected input impedance of the last said tube and including a condenser between grid and plate of the last said vacuum tube and a load resistor 50 in series with said plate whereby the input impedance of the last said tube exhibits a capacity reactance greater than the inductive reactance of said two coils in series at the resonant frequency of said tuned input coil. 55

5. In a selective carrier wave amplifier, means for varying the selectivity of said amplifier comprising the combination of at least two resonant circuits and a coupling link between said circuits, 60 said link comprising in series at least one coil magnetically coupled to each of said resonant circuits and the grid to cathode capacity of a thermionic vacuum tube, means for causing said grid to cathode capacity to vary as a function of the amplitude of the signals traversing said amplifier when said signals are greater than a predetermined amplitude.

6. The combination as set forth in claim 5 wherein at the frequency of resonance of said 70 resonant circuits the capacity reactance of said grid to cathode impedance is greater than the sum of the inductive reactances of said coils.

7. In the intermediate frequency amplifier of a superheterodyne radio receiver, the combina- 75

- tion of a plurality of thermionic repeaters, at least two pairs of input and output resonant circuits associated with said repeaters, energy transfer means linking said input and output circuits in said pairs, in which said transfer means comprises series circuits consisting of a coil coupled to an input circuit and a second coil coupled to the output circuit of a pair and the input impedance of a thermionic vacuum tube and means for causing said input impedance to exhibit a capacity reactance component greater in magnitude than the sum of the inductive reactances of said two coils at the intermediate frequency of said receiver.
8. The combination as set forth in claim 7 and including means for applying a control bias to said vacuum tube which is proportional to the difference between an initial fixed bias and a bias derived by rectification of the signal traversing said amplifier.
9. The combination as set forth in claim 7 in which the said vacuum tube embodies a cathode, a grid and a plate, and is associated with an external circuit comprising a capacity connected between said grid and said plate and a resistor in series with said plate and means for applying a control bias to said grid equal to the difference between a fixed voltage and a voltage derived by rectification of the signal traversing said amplifier.
10. In a carrier wave amplifier, the combination of at least two thermionic repeaters, a resonant circuit connected to the plate of one of said repeaters and a second resonant circuit connected to the grid of another of said repeaters, two coils and the input impedance of a thermionic vacuum tube connected in series, wherein one of said coils is magnetically coupled to said plate connected resonant circuit and the other of said coils is magnetically coupled to said grid connected resonant circuit, said vacuum tube including a cathode, a grid and a plate, means associated with said vacuum tube including a capacity connected between said tube grid and said tube plate, a resistance connected between said tube plate and a source of positive potential, and external grid bias means comprising a source of fixed bias and the direct current component of rectification of the signal traversing said amplifier acting in opposition wherein the input impedance of said vacuum tube exhibits a capacity reactance component of greater magnitude at all times than the inductive reactance of the two said coils in series at the resonant frequency of one of said resonant circuits.
11. The combination as set forth in claim 10 wherein said fixed bias is greater than that re-

quired to produce plate current cut-off in said vacuum tube.

12. The combination as set forth in claim 10 wherein the capacity reactance component of said vacuum tube input impedance is a function of the amplitude of the signal traversing said amplifier when said signal is greater than a predetermined value.

13. In a radio receiver embodying thermionic vacuum repeater tubes, the combination of at least one interstage coupling system comprising an input and an output tuned circuit and an intercircuit coupling impedance, said coupling impedance consisting of inductive means resonated to a frequency greater than the resonant frequency of either of said tuned circuits by an electrically controlled capacity means comprising the dynamic grid to cathode capacity of a thermionic vacuum tube wherein said combination includes a condenser connected between grid and plate of the last said vacuum tube.

14. In a selective system, the combination of two tuned circuits and intercircuit coupling means comprising two coils and the dynamic grid to cathode impedance of a thermionic vacuum tube triode connected in series, wherein one of said coils is coupled to one of said tuned circuits and the other of said coils is coupled to the other of said tuned circuits and including a condenser connected between the grid and plate of said triode wherein said condenser has a reactance greater than the combined inductive reactances of said two coils.

15. In a carrier wave amplifier, automatic band-pass control means comprising a thermionic vacuum tube feeding a tuned circuit, a second tuned circuit feeding into a second thermionic vacuum tube, two coils and an electronically controlled capacity connected in series, wherein one of said coils is magnetically coupled to the first of said tuned circuits and the second of said coils is magnetically coupled to the second of said tuned circuits and wherein said electronically controlled capacity comprises the effective grid to cathode capacity of a third thermionic vacuum tube, said third tube comprising at least a cathode, grid and plate, and further means comprising a condenser connected between plate and grid of said third tube and a load resistor in series with the plate of said third tube, means for applying a bias to the grid of said third tube at least in part derived from the rectification of signals traversing said amplifier wherein the minimum value of said electronically controlled capacity resonates said two coils in series to a frequency greater than the resonant frequency of either of said tuned circuits.

ALFRED W. BARBER.
